US00D801959S

(12) **United States Design Patent** (10) **Patent No.:** **US D801,959 S**
(45) **Date of Patent:** **** Nov. 7, 2017**

(54) **PORTABLE ELECTRONIC DEVICE**

(71) Applicant: **HTC CORPORATION**, Taoyuan (TW)

(72) Inventors: **Yien-Chun Kuo**, Taoyuan (TW);
Hung-Yi Huang, Taoyuan (TW);
Feng-Chen Chang, Taoyuan (TW);
Shih-Hsun Ou, Taoyuan (TW);
Chih-Ling Chien, Taoyuan (TW)

(73) Assignee: **HTC CORPORATION**, Taoyuan (TW)

(**) Term: **15 Years**

(21) Appl. No.: **29/553,256**

(22) Filed: **Jan. 29, 2016**

Related U.S. Application Data

(63) Continuation of application No. 29/443,348, filed on Jan. 16, 2013.

(51) **LOC (10) Cl.** **14-03**

(52) **U.S. Cl.**

USPC **D14/248**

(58) **Field of Classification Search**

USPC ..... D14/138 G, 138 AD, 341, 138 R, 496,

CLAIM

The ornamental design for portable electronic device, as shown and described.

DESCRIPTION

FIG. 1 is a front perspective view of a portable electronic device in accordance with our new design;

FIG. 2 is another front perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a rear perspective view thereof; and,

FIG. 10 is another rear perspective view thereof.

The broken lines which show portions of an electronic device form no part of the claimed design.

1 Claim, 9 Drawing Sheets
